Refiled for abandoned application Serial No.
542,668, June 6, 1931. This application Jan-
uary 26, 1937, Serial No. 122,482

8 Claims. (Cl. 123—97)

This invention relates to an improved construction of internal combustion engine. This application is a refile for abandoned application, Serial No. 542,668 for an Internal combustion engine, filed June 6, 1931.

As is well known, different internal combustion engines have different numbers of cylinders: for instance, different automobile engines today have four, six, eight, twelve, and sixteen cylinders, respectively. While automobile engines employ an even number of cylinders, an odd number of cylinders is found in airplane engines.

With the present-day type of internal combustion engine all of the cylinders are active during all stages of operation of the engine with the consequent consumption of fuel in corresponding degree. Also, the engine is subjected to a more or less increasing degree of heat developed by the constant explosions within all of the cylinders and there is also detracted from the power of the engine a certain degree of driving force which is required for operation of the conventional fan.

For some years past, there have been numerous attempts to improve the efficiency of the internal combustion engine by varying the number of cylinders, each engine of a given number of cylinders possessing certain advantages for certain purposes and under certain conditions. However, any engine of a given number of cylinders lacks efficiency when operated under certain conditions and for certain other purposes. That is, the present type of internal combustion engine of a given fixed number of cylinders does not possess flexibility adapting it for operation under various conditions with uniform maximum efficiency. The common tendency has been to increase the number of cylinders in all internal combustion engines.

Also, it is well known that in any given engine there is a certain definite point of speed at which it operates with its greatest possible degree of efficiency. Such point corresponds to a comparatively high number of revolutions per minute, with open throttle, which means comparatively high compression of the gas within the cylinders. Such compression in all of the cylinders, as above explained, means comparatively high consumption of fuel and a correspondingly high cost of operation.

With the above conditions well known to those who are familiar with the art to which the present invention relates, various attempts have been made to attain a higher degree of efficiency and economy in the operation of automobile engines as well as other engines through all stages of

operation, including the initial starting period under inertia and the period of building up comparative speed and the later period of maintaining such speed with the advantage of momentum.

One such attempt at the conservation of power in the operation of an engine is recognized in the well known gas-electric combination in which the gas engine is operated at a constant rate of speed for generation of electric current which is stored in a battery or batteries from which it may be drawn according to demands of the various stages of operation of the machine to which the engine is applied. In this way, the excess generated power is stored until required for use.

Another such attempt has been made in the art of steam engines in which there has been provided an auxiliary "booster" which is employed only temporarily during the stages of initial starting.

"Free wheeling" is another attempt to conserve energy which might otherwise be wasted in the operation of an automobile engine. By means of "free wheeling", advantage is taken of the momentum of the automobile with the result that less power is required to be developed and delivered by the engine during such continued operation. "Free wheeling" has, however, been considered quite unsafe because of the comparative lack of control of the operator at all times, which is due to the one-way disconnection of the driving force of the engine from the propeller shaft. Also, "free wheeling" involves special manipulation in connection with the gears.

The general objects of the present form of invention are the same as those set forth in the above-mentioned application, and therefore, there will be here mentioned only the more specific objects and advantages which are peculiar to the particular arrangement herein set forth.

Whereas the construction disclosed in the application above referred to includes means for manual adjustment by the operator, the present improved construction embodies an automatic control means, as will be more fully set forth.

Accordingly, the object of the present form of invention is to devise an internal combustion engine which in itself possesses a flexibility adapting it for operation under various conditions and with corresponding increased efficiency, and in which the change from one set of active cylinders to another set is effected automatically according to the operating conditions of the engine.

More specifically, the object of the present invention is to devise an internal combustion engine in which a part of the total number of cyl-

inders may be automatically rendered inactive after the engine has attained proper speed so that the engine may then continue in its operation with only a part of the entire number of 5 cylinders active and with the benefit of momentum.

A more specific object consists in devising such an engine in which a part of the cylinders will be rendered inactive by shutting off the supply of 10 fuel thereto, this operation being effected automatically by a certain predetermined condition of the throttle control means.

Another object consists in devising such an engine in which the automatic control will be effected in accordance with the condition of the 15 throttle control means and there will be effected simultaneously a reduction in the supply of fuel to the carburetor so as to automatically reduce the fuel consumption.

20 A further object consists in devising such an engine in which the automatic control by the throttle regulation in effecting the elimination of certain cylinders from active condition is through the instrumentality of an electrical 25 means.

Another object is to devise such an engine in which there is provided a combined, selective 30 switch control means whereby the engine may be operated with all of the cylinders active at all times according to standard operation, or the engine may be operated at all times with only a 35 reduced number of active cylinders, or the engine may be operated with the automatic control means above briefly referred to.

35 Another object consists in devising such an engine in which the combined switch control mechanism is embodied together with the ignition switch upon the dash-board of the automobile.

40 Other objects will appear from the following description and claims when considered together with the accompanying drawings.

Fig. 1 is a top plan view of the manifold which is adapted to be connected to the standard form 45 of automobile engine and which embodies my present form of engine; Fig. 2 is a side elevation of the manifold and carburetor with the automatic control connection therebetween together with dashboard switch and electrical connections; Fig. 3 is an elevation of the same as viewed 50 from the front of the engine; Fig. 4 is an inverted plan view of the same; Fig. 5 is an enlarged view of the electric control switch mechanism at the throttle; Fig. 6 is an enlarged view of the electric switch mechanism at the motor; Fig. 7 is a 55 sectional view taken on line 7-7 of Fig. 2; Fig. 8 is a diagrammatic view of the carburetor showing all valves, passages and conduits.

It is to be understood that the present disclosure is merely for purposes of illustration and that other modifications and variations may be made without departing from the spirit of the 60 present invention as herein set forth and claimed.

65 In the present illustration, the carburetor is indicated in a general way by reference numeral 1 while the manifold is indicated by reference numeral 2 and the intermediate tubular connection by reference numeral 3. It is to be understood that this invention may be applied to any 70 size or type of engine embodying any number of cylinders, as for instance, two, four, six, eight, or any other number. The manifold 2 has its arms 2^a and 2^b connected to the engine block, 75 each of these arms supplying fuel to one-half

of the total number of cylinders. The engine here shown has six cylinders.

According to the present invention, the manifold is provided with a rotatably adjustable valve 4 which is located between the connection of the tubular member 3 and the branch arm 2^b. The purpose of the valve 4 is to permit the manifold to be closed at this point against the passage of gas to the branch arm 2^b, and to thereby eliminate a part of the cylinders from active operation. The valve 4 is adapted for adjustment by means of the endless sprocket chain 5 which extends about the sprocket 6 mounted upon the one end of the shaft which carries the valve 4. This valve is normally opened and held in such open 10 position by means of the spring 7 which is anchored at its one end to the manifold, as indicated at the point 8, while its other end extends about the operating shaft of the disk 4 and is connected thereto, as indicated by reference 20 numeral 9.

The motive means for operation of the endless chain 5 so as to open valve 4, comprises the electric motor 10 which is mounted upon a suitably arranged bracket just above the manifold and 25 which carries upon its rotor shaft a sprocket 10^a which has driving connection with the endless chain 5. The same chain 5 extends also about another sprocket 11 which is mounted upon the end portion of the manifold and which is adapted 30 to operate a valve 12 for controlling the admission of atmospheric air through the open end of the manifold and into the engine through the branch arm 2^b. That is, the valves 4 and 12 are so constructed and arranged that when the 35 valve 4 is closed so as to prevent supply of fuel to those cylinders which are at other times supplied through the branch arm 2^b, the valve 12 will at the same time be caused to occupy open position so as to permit admission of atmospheric 40 air through the open end of the manifold and through the branch arm 2^b to the cylinders which have been rendered inactive. Such closing of the valve 4 and opening of the valve 12 is effected by means of the electric motor 10 while the adjustment of these two valves to reverse positions is effected by means of the spring 7 when they are released from the influence of the electric means. 45

Attached to the end of the shaft of the valve 4 is an extensible connecting means which provides operative control connection between the valve 4 and a part of the means which controls the supply of gasoline to the carburetor. This connecting means comprising the upper and lower parts 13 and 14 which have the extensible 55 connection 15.

The lower end of the connecting member 14 has operative connection at the point 16 with the upper end of the valve rod 17 which is provided upon its lower end with the conical shaped valve 18 adapted to seat within the cylindrical chamber 19 for a purpose to be described. The chamber 19 is mounted upon the side wall of the gasoline chamber 20 which forms part of the carburetor and through the port 21 of which the 60 gasoline is adapted to pass into the chamber 19 at a point above the valve 18. The valve 18 is normally closed by means of the coil spring 22 which surrounds the valve stem 17 and engages the abutment 23 on the valve stem 17 while at 70 its other end it engages the screw plug 24 in the upper end of the cylindrical chamber 19.

The passage 25 which is controlled by the valve 18 is divided into two parts, one of which extends from the bottom projection 19^a of the cylindrical 75

chamber 19 and has communication through the tube 26 with the bottom of the main part of the carburetor 1, as indicated at the point 27. The passage through the extension 19^a is controlled by the valve 28. The other outlet from the bottom of the cylindrical chamber 19 has communication through the tube 29 with the cylindrical chamber 30. The chamber 30 is attached to the side of the regular cylindrical chamber 31 and has communication with an auxiliary jet in the main part of the carburetor through tube 32. The chamber 31 is attached to the side of the chamber 20 and has communication with the interior thereof by means of a port through the wall thereof, and the chamber 31 has communication with the bottom of the carburetor 1 by means of the interconnecting passage 33. Chamber 31 and connecting passage 33 are conventional parts on the carburetor illustrated. There is provided also a port connection from the chamber 20 through the interconnecting tube 34 which enters the main part 1 of the carburetor at the point 27. This port may be controlled by the adjustment 35. It is to be understood that the control connections 34 and 35 as well as the chamber 31 and its connecting passage 33 and control means are to be recognized as parts of a standard form of carburetor which is already well known and to which the chambers 19 and 30 have been added for a purpose to be now explained. In this carburetor there can also be recognized the choke valve control A, the gasoline inlet B, the float C, the air valve D, and the adjusting means E therefor.

As in the familiar type of carburetor just now referred to, including the cylindrical chamber 31, the switch lever 36 has suitable lever connection with the valve 37 which is adapted for adjustment within the chamber 31 for varying the quantity of gasoline to be supplied to the carburetor. This control connection between the throttle and the valve 37 comprises the connecting link 37^a which is connected at the point 37^b to the plate 36^a rotatably adjustable about the axis 36^b. The plate 36^c upon which the electric switch is mounted has an arm 36^d connected at the point 36^e to the plate 36^a and arm 36^d of said plate 36^c is provided with the adjustable screws 36^f for engagement by the switch lever 36 which extends therebetween. By means of the stationary brake shoe 36^g which engages the periphery of the plate 36^a, this plate and the arm 36^d will remain in the position to which adjusted until the switch lever 36 engages one of the screws 36^f. Switch lever 36 can thus be adjusted so as to vary the number of active cylinders prior to changing the position of the throttle.

The auxiliary cylindrical chamber 30, which has been provided as part of the present improved construction, is provided also with a valve 39 which is adapted to control the flow of gasoline through the chamber 30 and which is connected at its upper end by means of the lever arm 40 to the lever arm 37^a which is manipulated in conjunction with the throttle control. The throttle control may be manipulated as usual by means of the lever connection from the steering wheel or from the floor board of the automobile through operative connections at the point 41 with switch lever 36.

The automatic control means for effecting operation of the electric motor 10 and the resulting adjustments of the parts heretofore referred to, will now be described. The electric circuit of the

motor 10 is controlled by a switch which is located in proximity to the throttle and which is supported upon the plate 36^c. This switch comprises the fixed point 42 which has an insulated base and the adjustable switch arm 43 which is pivoted at the point 44 upon suitable insulation. Upon the underside of this switch arm there is a projection 45 which is adapted to be engaged by a projection 46 on the hub of the switch lever 36. That is, upon actuation of the switch lever 36 in clockwise direction, as viewed in Fig. 2 of the drawings, so as to open the throttle, the projection 46 will engage the projection 45 so as to break the contact between the points 42 and 43 and thereby open the circuit. The contact point 42 is connected by means of the wire 47 to the point 48 on the switch plate which embodies the ignition switch as part thereof and which is conveniently located upon the dash-board of the automobile. This switch mechanism on the dash-board is controlled by means of the switch lever 49 which is pivoted in the usual manner at the point 50, to which point there is connected the wire 51 which is grounded at the point 52 through the storage battery 53. Other switch connections at this point will be later referred to.

The point 44 of the switch arm is electrically connected to the point 54 to which is connected also the wire 55 which leads to the one side 56 of the electric motor. The other side of the electric motor is connected by means of the wire 57 to the point 58 on a switch plate which supports the pivotally mounted switch arm 59. This switch arm carries the contact point 60 which is adapted for electric contact with the stationary contact point 61 which in turn is grounded, as indicated at 62. Upon the lower side of the switch arm 59, there is provided the projection 64 which is adapted for engagement by the projection 63 on the hub of the rotatably adjustable valve 12.

With the automatic electric control mechanism above described, it will be seen that upon moving the switch lever 36 by adjustment of the same in clockwise direction, as viewed in Fig. 2, the electric contact 42-43 will be automatically broken and as a result, the circuit through the motor 10 will also be broken. During such inactive condition of the motor 10, the spring 7 will cause the valve 4 to be opened and the valve 12 to be closed. Under such conditions, all of the cylinders of the engine will receive gas from the carburetor to as full an extent as permitted by the position of the throttle which is at all times under regular control of the operator. By the same operation, the valves 37 and 39 will be opened but not until the valves 4 and 12 have been adjusted and the switch lever 36 caused to engage one of the screws 36^f. Thus, the passage to the cylinders will first be opened and then the supply of gasoline to the carburetor and gas to the cylinders increased accordingly. This is the condition under which the engine will be started and the supply of fuel to the engine can be increased in the usual manner to any extent desired. Then when the inertia of the automobile has been overcome and there has been attained a certain desired rate of speed with corresponding momentum, the operator may permit the switch lever 36 to return to such position that the contacts 42-43 will be permitted to close and thereby close the electric circuit through the electric motor 10. This circuit will then include the battery 53, the switch 49, the wire 47, contact points 42-43, terminal 54, wire 75

55, through the electric motor 10, terminal 58, switch arm 59, contact points 60—61, and back to the ground. With the motor thus energized, it will cause operation of the sprockets about which the endless chain 5 extends, and as a result, the valve 4 will be closed and valve 12 will be opened so as to occupy positions indicated in Fig. 2. This operation of the sprockets will cause an extension of the spring 7 which upon de-energization of the electric circuit, will automatically return the valves 4 and 12 to reverse positions, as above explained. Then immediately following this operation by the motor 10, valve 17 will close so as to cut off the supply of gasoline. There may be effected further reduction in the fuel supply in the usual manner to the extent desired by closing throttle valve.

Such rotatable adjustment of the sprocket 11 will cause the projection 63 to engage the projection 64 on the switch arm 59 so as to break the circuit through the contacts 60 and 61. This breaking of the circuit takes place, however, only and immediately upon movement of the arm 65 upon the shaft of the sprocket 11 so as to engage and be held by the magnet 66, which is grounded, as indicated at 67. In this way, the motor 10 is replaced by the magnet 66 which then holds the parts in position to which they have been adjusted until the circuit is broken at the switch 42—43 by means of the throttle. Upon the circuit being broken through the motor 10 and established through the magnet 66, the electric connection thereby established will extend through the wire 55 which is connected at one end of the magnet. The purpose of replacing the motor by the magnet is to save electric current, the amperage of the magnet being considerably less than that of the motor.

With the combined electric switch in the position indicated in Fig. 2, it is possible to operate the present device in the manner above described, that is, with the automatic control as to the number of active cylinders and the supply of fuel thereto. However, upon adjustment of the switch lever 49, so as to engage the contact point 69, the engine may be operated in the same manner as the present standard form without any control or modification so far as the number of active cylinders is concerned; that is, with the switch in such position, the automatic control mechanism above described will be entirely cut out of the circuit and all of the cylinders of the engine will be active at all times. Then when it is desired to operate the engine with only part of the cylinders active at all times and without any automatic control for variation of the reduced number of active cylinders, this may be accomplished by adjustment of the switch arm 49 so as to engage the contact point 70 which has direct connection through the wire 71 with the lead 54 and thereby with the wire 55 and the remaining part of the electric circuit, as above described. That is, in this case, the switch 42—43 at the throttle will be out of the control circuit so that the adjustment of the throttle will have no effect whatever as to the number of active cylinders. This circuit is, however, still effective in the actuation of the electric motor 10 and the subsequent substitution of the magnet 66 so as to replace the motor in the manner above described and thereby actuate the valves 4 and 12 and maintain the same in the positions indicated in Fig. 2.

Thus, it will be seen that I have provided a divided means of controlling the supply of gaso-

line to the carburetor and that upon actuation of the automatic control means above described, the number of active cylinders will be reduced as a result of the closing of valve 4 and simultaneously there will be effected an elimination of one of the passages through which the gasoline is supplied to the carburetor. That is to say, upon such automatic adjustment and the consequent exclusion of the gas from the auxiliary arm 2^b of the manifold, the lever arm 13 will be lowered so as to release the rod 14 and thereby permit the valve 18 to be closed by the spring 22 so as to prevent any further passage of the gasoline through the chamber 19. As a result, the chamber 30 becomes idle since no gasoline is permitted to pass therethrough and likewise gasoline will no longer be supplied through the tubular connection 26. The gasoline supply to the carburetor is varied also by manipulation of valves 37 and 39, as above explained. With my arrangement, the supply of fuel is reduced to approximately one-half of the quantity ordinarily supplied to the total number of cylinders so that the quantity of fuel now corresponds to that required for the reduced number of active cylinders. This reduced quantity of fuel is then supplied only through the tube 34 and directly from the chamber 20 into the chamber 31 and through the passage 33. However, upon reverse adjustment of valve 4, the cylinders which were rendered inactive, will be caused to resume active condition and fuel will be supplied thereto. It is to be understood that the tubular connections for the fuel supply are of comparatively reduced size and are of proper dimensions for supply of gasoline therethrough in the manner and proportions as herein explained. If so desired, there may be employed separate carburetors of proper individual capacity for the different combinations of cylinders instead of a single carburetor.

In actual practice, the engine will preferably be started with all of the cylinders active so as to facilitate starting of the car during the initial period when it is necessary to overcome its inertia. During such operation with all of the cylinders active, the valve 4 will occupy open position and fuel will be supplied through all of the several connections from the chamber 20 to the carburetor 1. Then when sufficient speed has been attained in order to derive advantage of the momentum of the automobile, the control lever 36 will be manipulated so as to permit the switch to close, whereupon valve 4 will be adjusted automatically so as to exclude the gas from the arm 2^b of the manifold and thereby reduce the number of active cylinders while at the same time and by the same manipulation, the quantity of gasoline supplied to the carburetor and gas to the manifold will be reduced in corresponding degree and atmospheric air will be admitted to the idle cylinders. The throttle may of course be adjusted at will in the usual manner for regulating the flow of gas to the active cylinders, as above explained.

Actual experience with my present invention has shown that when a certain rate of speed has been attained in the operation of an automobile, the full power of all of the cylinders is not necessary in order for the automobile to continue to proceed at substantially the same rate of speed under favorable conditions of travel. This is due to the factor of momentum of which the present invention is designed to take advantage, at the same time introducing other advantageous

features and without the introduction of any objectionable characteristics, such for instance as loss of control of the automobile at any time. According to the present invention, the engine is always in gear and is therefore under complete control of the operator at all times.

With this device, there is realized the further advantage of automatically shifting from one number to another number of active cylinders, which may be considered the practical equivalent of shifting from one gear ratio to another in the present standard form of automobile. This new manner of operation may be termed "cylinder shift". The practical significance of this comparison is appreciated when full consideration is given to the manner of operating my present device, first, with all of the cylinders active during the initial period of starting, and then with only a reduced number of cylinders remaining active during the continued period of operation and so forth, as before explained. I thereby obtain practically the same result as in the familiar shifting of gears. Any desired degree of compression of the gas may be obtained at any time in the active cylinders by adjustment of the throttle. For instance, the reduced number of cylinders can be operated at full compression or reduced compression.

The admission of outside air into the idle cylinders will absorb and carry off sufficient excess heat of the engine to maintain the same at an efficient operating temperature. The benefit of such dissipation of engine heat is transmitted through the entire engine block by means of the water jacket which surrounds all of the cylinders. Since the air is drawn in through a separate channel, the idle cylinders are always filled completely with air and there is no back pressure upon the intake stroke of the pistons.

Also, the air from the idle cylinders will reduce the temperature and hence the volume of the exhaust and thereby facilitate the discharge thereof through the muffler of the exhaust.

The air from the idle cylinders will also dilute the carbon monoxide of the exhaust.

While according to this invention, I take advantage of momentum, yet the car is not released to the dangerous condition of coasting. Thus the advantages of this invention may be enjoyed without such danger and the present invention is also free of troublesome gears in the "cylinder shift" from one engine operating condition to another.

With this invention, there is realized a very marked saving in the fuel which means a decided saving in the cost of operation. This is realized not only when traveling with momentum but also when the car is idle and the engine is idling with low throttle. Likewise, the improvement as to the temperature of the engine means a reduced consumption of oil with the saving in cost and increased efficiency incident thereto. Also, all of the engine parts are relieved of the obvious danger of over-heating; there is less wear of the parts and longer life results. There is also obtained a smoother and more dependable operation.

Regardless of what may be the proper theory as to the cause of the various advantages which result from this invention, it is a demonstrated fact that there is hereto obtained smoother and more dependable operation under various operating conditions and in a more efficient and economical manner than heretofore known. Other advantages in addition to those above briefly re-

flected to, will be apparent to those who are familiar with the art to which this invention relates.

What I claim is:

1. In an internal combustion engine, the combination of a plurality of cylinders, means for supplying fuel to said cylinders, valve means for preventing fuel from entering some of the cylinders, means tending normally to open said valve means so as to permit entrance of fuel to the cylinders controlled thereby, and means controlled automatically according to the throttle opening for closing said valve means so as to render some of the cylinders inactive.

2. In an internal combustion engine, the combination of a plurality of cylinders, means for supplying fuel to said cylinders, valve means adapted to exclude fuel from and admit air to some of the cylinders, electrical means controlled by the condition of the throttle opening for so adjusting said valve means as to render some of the cylinders inactive, and means normally tending to render the inactive cylinders active upon discontinuance of the effect of said electrical means.

3. In an internal combustion engine, the combination of a plurality of cylinders, a divided intake manifold therefor, carburetor means for supplying fuel to the manifold, multiple means for controlling the flow of fuel to said carburetor means, a valve in one part of said manifold for controlling the flow of fuel therethrough, interconnecting means between said valve and multiple control means, and automatic means for actuating the same according to the throttle opening whereby the number of cylinders which are active may be varied and the supply of fuel to the carburetor varied accordingly by rendering one of said multiple means ineffective.

4. In an internal combustion engine, the combination of a plurality of cylinders, a divided intake manifold therefor, carburetor means for supplying fuel to the manifold, multiple means for controlling the flow of fuel to said carburetor means, a valve in one part of said manifold for controlling the flow of fuel therethrough, interconnecting means between said valve and multiple control means, and automatic electrical means for actuating the same according to the throttle opening whereby the number of cylinders which are active may be varied and the supply of fuel to the carburetor varied accordingly by rendering one of said multiple means ineffective.

5. In an internal combustion engine, the combination of a plurality of cylinders, means for supplying fuel thereto, automatic control means whereby the number of cylinders which are active may be automatically varied according to the throttle opening and means for rendering said automatic control means ineffective so as to render all of the cylinders active at all times.

6. In an internal combustion engine, the combination of a plurality of cylinders, means for supplying fuel thereto, electrical control means whereby the number of cylinders which are active may be automatically reduced according to the closing movement of the throttle during the full running period and switch means for rendering said control means ineffective so as to render all of the cylinders active at all times.

7. In an internal combustion engine, the combination of a plurality of cylinders, means for supplying fuel thereto, automatic control means whereby the number of cylinders which are active

may be varied according to the throttle opening, and means for rendering said automatic control means ineffective so as to render only a part of said cylinders active at all times.

5 8. In an internal combustion engine, the combination of a plurality of cylinders, means for supplying fuel thereto, automatic control means

whereby the number of cylinders which are active may be varied according to the throttle opening, and selective means for rendering said automatic control means ineffective so as to render either all or only a part of the cylinders active 5

JOHN F. WERDER.
